(57) **CLAIM**

The ornamental design for a display screen with an animated graphical user interface showing a payment slider, as shown and described.

DESCRIPTION

FIG. 1 illustrates a display screen with an animated graphical user interface showing a first image in a sequence according to a first embodiment;

FIG. 2 illustrates a second image thereof;

FIG. 3 illustrates a display screen with an animated graphical user interface showing a first image in a sequence according to a second embodiment; and,

FIG. 4 illustrates a second image thereof.

The outermost broken lines depict the display screen and form no part of the claimed design. The remaining broken lines depict portions of the graphical user interface and form no part of the claimed design. The broken lines including the text showing “new payment”, “pay”, and “request” are not part of the claimed design.

The appearance of the animated graphical user interface sequentially transitions between the images shown in FIGS. 1-2 and FIG. 3-4. The process or period in which an image transitions to another forms no part of the claimed design.

1 Claim, 4 Drawing Sheets
